UNITED STATES PATENT OFFICE

F. ROBERT SEIDENSTICKER, OF WEST MERIDEN, CONN., ASSIGNOR TO
BRADLEY & HUBBARD MANUFACTURING COMPANY, OF SAME PLACE.

DESIGN FOR LAMP-BRACKETS.

Specification forming part of Design No. **11,465**, dated October 21, 1879; application filed September 19, 1879.
[Term of patent 7 years.]

To all whom it may concern:

Be it known that I, F. ROBERT SEIDENSTICKER, of West Meriden, in the county of New Haven and State of Connecticut, have invented a new Design for Lamp-Brackets; and I do hereby declare the following, when taken in connection with the accompanying drawing and the letters of reference marked thereon, to be a full, clear, and exact description of the same, and which said drawing constitutes part of this specification, and represents a side view.

This invention relates to a design for lamp-bracket arm, with a support for the lamp-fount; and it consists in the configuration, as hereinafter described, and shown in the accompanying illustration.

The general outline of the bracket is of what is known as "U shape," springing from a vertical post, *a*, by a scroll-work upward, outward, and downward, and from this starts a second part or main body of the arm, united to the first by a boss, *b*, thence curving downward, outward, and upward in three branches, the space between the two outer filled by a succession of lancet-points, with the representation of a cock and key at the lowest or central part of the main arm. A branch extends from the tip near the boss across, and connecting the three parts, and terminating in a scroll-work in rear of the main arm, all as shown in the accompanying illustration.

The basket for the support of the fount con-

sists of a bottom resting on the outer end of the bracket-arm, and from which rise several arms expanding or outwardly inclined, and support at their upper end a ring consisting of a reeded molding, the bottom being correspondingly molded, the face of the vertical arms ornamented in shell-work pattern, as shown in the accompanying illustration.

The arm is applicable to a wall-bracket or to a chandelier.

The basket may be used upon brackets of other designs, or other designs of baskets may be used with the bracket. This application is therefore not to be understood as combining this particular basket with this particular bracket.

I claim—

1. The design for lamp-bracket arm, consisting of the scroll-work springing from the post *a*, the body of the arm consisting of three branches united, the space between the two outer filled by lancet-shaped points, all as shown in the accompanying illustration.

2. The design for basket for lamp-bracket arm, consisting of the reeded-edge bottom, outwardly-inclined posts, and reeded-shaped molded top, as shown in the accompanying illustration.

F. ROBT. SEIDENSTICKER.
